POSITIONING GAUGE

William C. Card, Jr., Winthrop, Mass., assignor
to Compo Shoe Machinery Corporation, New
York, N. Y., a corporation of Delaware

Application January 4, 1934, Serial No. 705,179

20 Claims.

(Cl. 12—25)

This invention relates to a positioning gauge capable of use in numerous different associations, but primarily intended to be employed in connection with the positioning of shoe soles with reference to a pattern therefor.

In its more specific aspects, the present invention aims to provide a gauge which is ideally adapted for the positioning of soles with reference to a pattern in a sole rounding or similar machine.

A further object of the invention is that of constructing a positioning gauge, the parts of which may be readily manipulated by a relatively inexperienced operator to rapidly and accurately bring a sole to its proper position.

A still further object is that of furnishing a gauge which will be automatically maintained in position until the parts of the machine grip or secure the sole so that there will be no danger of displacement.

Another object is that of furnishing a gauge, the parts of which will be automatically released upon the machine moving to a position at which displacement of the sole is substantially precluded.

Still another object is that of furnishing an apparatus of this character which will include relatively few parts, each individually simple and rugged in construction and capable of ready assemblage and replacement, to provide a gauge operating over long periods of time with freedom from difficulty.

With these and other objects in mind, reference is had to the attached sheets of drawings illustrating one practical embodiment of the invention, and in which:—

Fig. 1 is a partly sectional side elevation of a gauge, and showing the same in association with a sole rounding machine; and

Fig. 2 is a partly fragmentary plan view of the apparatus shown in Fig. 1.

In these views the numeral 5 indicates a base, from which a pedestal 6 may extend upwardly.

A collar 7 is normally fixed with respect to this pedestal by, for example, a set-screw 8, this collar serving—as hereinafter brought out—to support the gauge and associated structure in a proper plane. The pedestal is positioned adjacent a sole rounding machine, the clamping ram and bed of which have been diagrammatically indicated at 9 and 10, respectively. As is well known to those skilled in the art, a machine of this character serves to support a pattern 11 with

respect to which an inner sole 12 is to be properly

supported, so that the knife of the machine may cooperate with this sole to properly round or trim the same. The gauge of the present invention serves primarily to properly position the sole with respect to the pattern.

The gauge may conveniently include a bracket 13, which supports a slide 14. A spring 15 normally urges the slide to assume a retracted position, and a handle 16 may be secured to the slide so as to project the latter.

With a view to normally maintaining the slide against movement, the bracket 13 is provided in the present exemplification with an upstanding support or ear 17, to which a cam or detent 18 is pivotally secured by, for example, a pin 19.

In line with the end of this cam the bracket is formed with an opening so that the cam may bear against the upper face of the slide, it being noted that the depth of the cam is such that it may not be swung rearwardly through a vertical plane. Consequently, the cam edge will bear against the slide face and will function as a wedge to prevent the same being retracted. A releasing lever 20 may have its inner end pivotally secured, as at 21, to the bracket 13, and its outer end suitably contacted by a portion of the machine, so that, as such portion moves with respect to the gauge, the lever will be swung downwardly. The lever may slide in contact with the inner faces of a pair of ears 22

projecting upwardly from the bracket, and may at this point be engaged by a spring 23 which normally maintains the lever in an elevated position. The wedge or cam may be provided with a projecting portion 24, against which the end of a pin 25 bears, this pin being adjustably coupled to the lever 20, so that, as the latter swings downwardly, the cam 18 will swing forwardly and upwardly, thus releasing the slide. A spring 26

may cooperate with the under face of the projecting portion to thus normally urge the cam into locking contact with the upper face of the slide, it being understood that the resistance offered by this spring is not so great as to cause any difficulty in releasing the cam or wedge by movement of the lever 20. Likewise, this spring will not prevent a projection of the slide as the operator pushes the same forwardly by means

of the handle 16.

Secured to the outer end of the slide are a pair of arms 27, this connection being preferably established by means of a pin 28, with respect to which the arms may oscillate. These arms are normally drawn towards each other by a spring

29, a slotted link 30 serving to limit inward as well as outward movement of these arms with respect to each other. Mounted adjacent the outer end of each arm are a pair of rollers. These 5 rollers may, in each instance, embrace a cylinder 31 and a disk 32. The cylinder or disk may be relatively rotatable or not, as may prove most desirable, but it will be noted that the cylinder—in the present exemplification—has a circumference less than that of the disk, so that the disk 32, adjacent its point of contact with the pattern 11, will extend beyond the face of the roller 31 to an extent sufficient to assure a proper and corresponding projection on the part of the 10 sole 12 with respect to the pattern. In addition to serving as an arm limiting member, the link 30 acts in cooperation with the pattern 11 to prevent the slide from being projected to too great a distance. In other words, as the operator projects the slide, the link 30 will engage the forward edge of the pattern 11, thus functioning as a stop to prevent too great a projection on the 15 part of the slide. However, the link lies in a plane such that it will not engage the sole 12.

25 In operation it will be appreciated that if the present gauge is employed in association with a rounding machine, the latter may be driven in any desired manner and that soles may be placed in association therewith, either manually or by 20 any proper mechanism. After a sole is in position upon the pattern, the operator, by simply projecting the slide, will cause the rollers to move to a position at which they will engage the edge of the sole and move the latter rearwardly as well 25 as center the same with respect to the pattern. This movement will at all times be controlled by the limitation on the projection, in that, as afore brought out, the link will function as a stop. Upon the slide being projected to its maximum 30 extent, it will be found that the sole will be properly positioned with reference to the pattern, and it will also be noted that return movement of the slide is prevented incident to the provision of the cam or wedge 18. The clamping ram may 35 now move downwardly to secure the sole against further movement and, incident to such downward movement, the lever 20 will be swung to release the slide, and thus, under the influence of spring 15, the slide will be retracted. A re- 40 bound-cushioning element may be provided by securing to the slide a spring pressed head 33 which will engage the forward edge of the bracket 13, and consequently no damage will occur 45 incident to the sudden arrest of rearward movement of the parts. The rounding machine may now operate on the sole, and during such operation the entire gauge may be swung around the collar 7, if this is necessary. In any event, it 50 will be noted that the parts have been returned 55 to their initial position and are now in a condition where a second positioning operation may be resorted to.

Thus, among others, the several objects of the invention as specifically afore noted, are achieved. 60 It will be understood that numerous changes in construction and rearrangements of the parts might be resorted to without departing from the spirit of the invention as defined by the 65 claims.

70 Having thus described the invention, what is claimed as new and desired to be protected by Letters Patent is:

1. A positioning gauge comprising, in combination, opposed arms each having means to engage a sole to be positioned and means to engage

a pattern with reference to which said sole is to be positioned, a mounting for said arms movable to effect engagement between said pattern engaging means and a pattern, and means for holding said mounting in such position. 5

2. A positioning gauge comprising, in combination, opposed arms each having means to engage a sole to be positioned and means to engage a pattern with reference to which said sole is to be positioned, a mounting for said arms 10 movable to effect engagement between said pattern engaging means and a pattern, means for holding said mounting in such position and releasing means for said last named means.

3. A positioning gauge comprising, in combination, opposed arms each having means to engage a sole to be positioned and means to engage a pattern with reference to which said sole is to be positioned, a mounting for said arms movable to effect engagement between said 15 pattern engaging means and a pattern, means normally acting to retract said mounting and means acting automatically to render said last named means inoperative. 20

4. In combination, a positioning gauge and a 25 machine with reference to which an element is to be positioned; said gauge and machine having relatively movable parts; said gauge including a support, a projectable mounting on said support, means on said mounting for contacting and 30 positioning an element with reference to said machine when said mounting is projected; means for holding said mounting in such projected position; and means acting automatically upon one of the machine parts moving with reference 35 to said gauge to render said last named means inoperative.

5. In combination, a sole rounding machine including a pattern and a clamping ram movable toward said pattern; a gauge mounted adjacent said machine; said gauge including a movable mounting carrying means for contacting said pattern and means for contacting and positioning a sole blank with reference to said pattern, means for locking said mounting against 45 movement, and means including a member located in the path of and actuated by said ram for releasing said locking means. 40

6. A positioning gauge including, in combination, means providing a pattern contacting surface and a sole contacting surface for causing a sole to assume a proper position with reference to a pattern, a projectable slide connected to the means providing said surfaces, means tending normally to retract said slide, and means 50 for locking said slide in projected position. 55

7. A positioning gauge including, in combination, means providing a pattern contacting surface and a sole contacting surface for causing a sole to assume a proper position with reference to a pattern, a projectable slide connected to the means providing said surfaces, means tending normally to retract said slide, and means for normally rendering said retracting means inoperative. 60

8. A positioning gauge including, in combination, means to engage a sole and position the same with reference to a machine for operating on said sole, a horizontally projectable slide mounting said sole engaging means, and means 70 for locking said slide in projected position. 75

9. A positioning gauge including, in combination, means to engage a sole and position the same with reference to a machine for operating on said sole, a horizontally projectable slide 75

- mounting said sole engaging means, a spring co-operating with said slide to normally retract the same, and means for locking said slide in projected position.
- 5 10. A gauge including a bracket, a slide mounted by said bracket, a pair of arms pivotally mounted by said slide, sole and pattern engaging elements mounted adjacent the outer end of each of said arms, said slide being projectable bodily to move said arms to bring said elements into contact with a sole and pattern respectively, and a stop engageable with said pattern to limit the amount of projection of said slide.
- 10 11. A positioning gauge including, in combination, sole and pattern engaging elements, means for permitting projection of the same into contact with a sole and pattern to position the former with reference to the latter, and a stop for limiting the amount of such projection.
- 20 12. A positioning gauge including, in combination, sole and pattern engaging elements, means for permitting projection of the same into contact with a sole and pattern to position the former with reference to the latter, and means associated with said first named means to engage said pattern to limit the movement of said projecting means.
- 30 13. A positioning gauge including, in combination, a bracket, a slide mounted thereby, a pair of arms secured adjacent the forward end of said slide, sole and pattern engaging elements mounted adjacent the outer ends of said arms, and a pattern engaging stop connected to said arms.
- 35 14. A positioning gauge including, in combination, a bracket, a slide mounted thereby, a pair of relatively movable arms secured adjacent the forward end of said slide, sole and pattern engaging elements mounted adjacent the outer ends of said arms, and a slotted link connected to said arms to limit outward and inner movement of the same with respect to each other, said link being engageable with said pattern to act as a stop.
- 40 45 50 15. A positioning gauge including, in combination, a projectable slide having gauge elements thereon, means for retracting said slide, a wedge element cooperating with said slide to prevent such retraction, and wedge releasing means to be engaged by a machine part and operated thereby.
16. A positioning gauge including, in combination, a projectable slide having gauge elements thereon, means for retracting said slide, a wedge element cooperating with said slide to prevent such retraction, a lever mounted to move adjacent said wedge and connected thereto to release the same, and said lever being connectible to a machine part to be actuated thereby.
17. A positioning gauge including, in combination, a slide, opposed arms pivotally mounted on said slide, means normally urging said arms toward each other, means on each arm providing a pattern contacting surface and a sole contacting surface, said slide being projectable to engage said surfaces against a pattern and sole respectively, and a stop engageable with such pattern to limit the amount of such projection.
18. A positioning gauge including, in combination, a slide, opposed arms pivotally mounted on said slide, means normally urging said arms toward each other, means on each arm providing a pattern contacting surface and a sole contacting surface, said slide being projectable to engage said surfaces against a pattern and sole respectively, means tending normally to retract said slide, a stop engageable with such pattern to limit the amount of such projection, and means operative to hold said slide in projected position.
19. A positioning gauge including, in combination, means providing a pattern contacting surface and a sole contacting surface for causing a sole to assume a proper position with respect to a pattern, a projectable slide mounting said means providing said surfaces, means tending normally to retract said slide, means for frictionally engaging said slide to hold it in projected position, and means for releasing said holding means.
20. A positioning gauge including, in combination, a projectable slide, gauge means on said slide adapted to engage a rounding machine pattern and a sole to position the sole with respect to the pattern, means tending normally to retract said slide, a detent, spring means urging said detent into holding relation with said slide to hold it in projected position with said gauge means in contact with said pattern, and means for automatically releasing said detent upon operation of said rounding machine.

50 WILLIAM C. CARD, JR.
